UNITED STATES PATENT OFFICE

WALTER PORANSKI, OF CHICAGO, ILLINOIS, ASSIGNOR TO NORIDA PARFUMERIE, INC.,
OF LONG ISLAND CITY, NEW YORK, A CORPORATION OF NEW YORK

COMPACT

Application filed October 11, 1928. Serial No. 311,820.

My invention relates to housings which may be used as compacts or vanity cases, and has among its other objects the production of devices of the kind described which are extremely neat and attractive in appearance, convenient, durable, compact, and are quickly and easily re-filled.

A particular object of the invention is to provide containers or housings of the class described having improved means for fastening the housing members together.

Still another object is the provision of latching means which is simple in construction and inexpensive to manufacture.

Still another object is the provision of latching means for a housing which may be utilized as a mounting for a mirror and as a retaining means for a cake of cosmetic material or the like.

Many other objects and advantages of the construction herein shown and described will be obvious to those skilled in the art from the disclosure herein given.

To this end my invention consists in the novel construction, arrangement and combination of parts herein shown and described and more particularly pointed out in the claims.

In the drawings, wherein like reference characters indicate like or corresponding parts:

Fig. 1 is a perspective view of a housing taking the form of a compact in which the preferred embodiment of my invention is illustrated, the compact being shown as it appears when opened for use;

Figs. 2 and 3 are plan and elevational views respectively of the housing or compact as it appears when closed;

Fig. 4 is a sectional view along the line 4—4 of Fig. 2, drawn to a larger scale;

Fig. 5 is a transverse sectional view through the lower portion of the compact showing the mirror in both open and closed positions;

Fig. 6 is a perspective view of the compact as it appears when opened for use, the rouge and powder puffs having been removed;

Fig. 7 is a view of the latching device and the mirror mounted thereon as it appears when removed from the casing;

Fig. 8 is a view along the line 8—8 of Fig. 6;

Fig. 9 is a view along the line 9—9 of Fig. 7; and

Fig. 10 is a view along the line 10—10 of Fig. 6.

In the drawings I have illustrated the invention as embodied in a compact which includes a casing or container adapted to hold a mirror, rouge and powder cakes or the like.

The casing comprises a box member or container 15 and a lid member 17 which is fastened to the box member by a hinge 19. The box member 15 is provided with an annular flange 16 and the lid member 17 is correspondingly equipped with an annular flange 18, the flanges 16 and 18 being preferably constructed so that the flange 18 telescopes over the flange 16, when the casing is closed. The box member 15 and the lid member 17 are preferably provided with concave inner surfaces which provide space for cakes of powder, rouge, puffs or the like. These inner surfaces are preferably made concave since the capacity of the casing is thereby increased and a generally artistic effect is produced. The invention may, however, be as well embodied in a casing having its main walls comprising flat surfaces rather than concave.

A split or non-continuous ring 21 preferably constructed of spring steel or the like is positioned in the box member 15 in contact with the inner periphery of the annular flange 16. The resiliency of the ring 21 tends to its rectification and yieldingly holds it in close contact with the flange 16. A plurality of outstanding lugs 22 are formed on the ring 21. The lugs 22 frictionally engage the flange 16 and are seated in a groove 20 formed

at the junction of the flange 16 with the main body of the box member 15. The lugs 22 serve as detents which normally hold the ring 21 against movement along the periphery of the flange 16.

The ring 21 is so constructed as to provide means for latching the lid member 17 and the box member 15 together. For this purpose I have provided a stem 23 shown as integrally formed with the ring 21. The stem 23 projects outwardly from the flange 16 through a slot 25 provided for that purpose. A detent or clasp 24 is formed on the ring 21 preferably immediately above the stem 23. The 10 clasp 24 and the stem 23 are substantially alike in construction but the clasp 24 is shown as being shorter than the detent and as normally extending through a niche 26 formed in the upper edge of the flange 16. When 15 the casing is closed, the detent 24 is of sufficient length to engage a depression or indentation 27 which is formed for that purpose in the annular flange 18 of the lid 17. The stem 23 and detent 24 are preferably positioned near the end of the split ring 21 but may be located on any other portion of the ring. The latching means is released by pressing inwardly on the stem 23, the ring 21 yielding sufficiently to disengage the 20 detent 24 from the flange 18.

A plurality of inwardly extending lugs 29 are adapted to frictionally engage a pan 30 which contains a cake of powder 31. The ring 21, from which the lugs 29 project, is 35 adapted to yield under pressure sufficiently to permit the pan 30 to be easily removed for the purpose of replacement or renewal.

A mirror 32 is mounted upon the ring 21, being connected thereto by a hinge 33 which 40 permits the mirror to take the folded position shown in Fig. 4 or the open position shown in Figs. 1 and 6. It is obvious that the ring 21 performs a three-fold function as follows: a 45 latch for fastening the box member 15 and the lid member 17 together, a fastening means to hold a supply of cosmetic material stationary in the housing, and as a mounting means for a mirror.

In Fig. 7 I have shown the disassembled 50 ring 21, together with the mirror 32 which is mounted thereon, as it appears before being mounted in the casing. The split ring 21 is preferably made of spring metal. The resiliency of the ring 21 causes it to expand to a 55 larger diameter when disassembled. This resiliency serves to hold the ring securely within the casing and against the flange 16 once it is positioned therein, and permits its 60 easy removal should it be desirable to detach the ring 21 and mirror 32 from the casing. The mirror 32 is so mounted as to leave a space between it and the powder pan 30 when the 65 mirror is folded and the casing is closed. The space between the mirror and the pan 30 may

be used as a receptacle for a powder puff 45 or the like.

The lid member 17 is also utilized as a container for a cake of cosmetic material, preferably taking the form of a rouge cake 35 contained in a rouge pan 34. For this purpose I have provided an annular ring 36 which closely fits within the annular flange 18 of the lid member 17. The outer edge of the ring 36 is positioned in a groove 39 which is formed at the junction of the flange 18 with the main body of the lid member 17. The inner periphery of the ring 36 is provided with a flange 37 upon which are a plurality of inwardly extending lugs 38. The lugs 38 frictionally engage the side wall of the pan 34 and thereby yieldingly hold the pan in position and permit its easy removal for replacement. A rouge puff 42 is held in position upon the rouge cake 35 by a lip or lug 40 shown as integrally formed with the ring 36.

Thus it will be seen that I have provided a compact of the class described in which one of the outstanding features is an element taking the form of a split or non-continuous resilient ring preferably constructed of spring steel, said ring being so mounted as to adapt it to serve as a latching means for the casing, a mounting means for the mirror, and a holding means for cakes of material which may be positioned in the casing.

Having thus described my invention, it is obvious that various immaterial modifications may be made in the same without departing from the spirit of my invention, hence I do not wish to be understood as limiting myself to the exact form, construction, arrangement and combination of parts herein shown and described and more particularly pointed out in the claims.

What I claim as new and desire to secure by Letters Patent is:

1. A housing having a flanged side wall, a split ring detachably positioned about the inner periphery of the side wall, a cake positioned within the ring, means on the ring adapted to frictionally engage the cake, and a mirror hingedly mounted on the ring.

2. A housing comprising a box member and a lid member, a cake of cosmetic material positioned in the box member, a split ring partially encircling the inner periphery of the box member, means on the ring which forms a latch adapted to fasten said members in closed position, and detent means projecting from the ring adapted to frictionally engage said cake.

3. A housing comprising a box member and a lid member, a split ring detachably mounted in and partially encircling the inner periphery of the box member, means on said ring forming a latch to fasten said members in closed position, and a mirror hingedly mounted on said ring.

4. A housing comprising a box member and a lid member, a cake of cosmetic material positioned in the box member, a split ring detachably mounted in and partially encircling the inner periphery of the box member, means on said ring forming a latch to fasten said members in closed position, detent means on the ring adapted to frictionally engage said cake, and a mirror hingedly mounted on said ring.

10 In testimony whereof, I have hereunto signed my name.

WALTER PORANSKI.
